UNITED STATES PATENT OFFICE.

GEORGE W. SHIEBLER, OF BROOKLYN, NEW YORK.

DESIGN FOR METALLIC BORDER.

SPECIFICATION forming part of Design No. 23,517, dated July 31, 1894.

Application filed July 2, 1894. Serial No. 518,381. Term of patent 3½ years.

To all whom it may concern:

Be it known that I, GEORGE W. SHIEBLER, a citizen of the United States, residing at Brooklyn, in the county of Kings and State of New York, have invented a new Design for a Metallic Border, of which the following is a specification.

The leading feature of this metallic border consists in the design of a series of inclined pear shapes in relief with intermediate curved scrolls single at one end and double at the other.

This design is shown in the accompanying drawing.

The convex figures *a*, are pear shaped and inclined to the general direction of the border and between them are the curved scroll ornaments *b*, with a single curve at one end and a double curve at the other end.

I claim—

The design for a metallic border substantially as shown and described.

Signed by me this 26th day of June, 1894.

GEO. W. SHIEBLER.
